UNITED STATES PATENT OFFICE.

RALPH M. LOVEJOY, OF BOSTON, MASSACHUSETTS.

ANTIFRICTION-BEARING MECHANISM FOR SPRING SHACKLES.

Continuation of application Serial No. 551,584, filed April 11, 1922. This application filed January 20, 1923. Serial No. 613,890.

To all whom it may concern:

Be it known that I, RALPH M. LOVEJOY, a citizen of the United States, and a resident of Boston, county of Suffolk, State of Massachusetts, have invented an Improvement in Antifriction-Bearing Mechanism for Spring Shackles, of which the following description, in connection with the accompanying drawing, is a specification, like 10 characters on the drawing representing like parts.

This invention relates to spring shackles for vehicles and comprises certain improvements upon the construction disclosed in 15 my prior Patent 1,467,051, granted September 4, 1923.

The principal object of the invention is to provide a spring shackle comprising a casing adapted to be connected to the frame 20 of a vehicle and having a swinging member pivotally mounted in said casing and also pivotally connected to the spring, with means for more effectively resisting lateral movement of said swinging member.

25 A further object of the invention is to provide a construction comprising a swinging member pivotally mounted in the casing and having laterally extending trunnions with more effective and durable bearings 30 and also with a simplified and improved means for preventing lateral movement of the swinging member.

The construction disclosed in my prior 35 application comprises a casing adapted to be secured to the frame of a vehicle having a swinging member provided with flat faces and laterally extending trunnions mounted to swing about a horizontal axis in said casing and provided with means for 40 pivotally securing the same to the spring. In that construction the trunnions of the swinging member were mounted in cup-shaped bearing members with a cup-shaped anti-friction device enclosing the trunnions, 45 the specific anti-friction device disclosed therein comprising oil-soaked wood cut diagonally of the grain.

The present construction differs from that 50 disclosed in the previous application in that the lateral movement of the trunnion is prevented by sleeves of larger diameter than the trunnions, surrounding the trunnions, said sleeves being longer than the trunnions and abutting at their inner ends against the

flat faces of the swinging member and prevented from longitudinal movement.

A further feature of the invention consists in interposing between the sleeves and the trunnions a bearing of anti-friction material, preferably oil-soaked wood, with the grain extending vertically so that the ends of the fibres engage the upper and lower portions of the trunnions where, of course, the greatest wear occurs.

These and other objects and features of 65 the invention will more fully appear from the following description and the accompanying drawings and will be pointed out in the claims.

A preferred embodiment of the invention 70 is illustrated in the accompanying drawings, in which,

Fig. 1 is a side elevation of the end portion of the frame and of the spring of an automobile connected by a spring shackle 75 embodying the invention;

Fig. 2 is a sectional view on line 2—2 Fig. 1, certain portions, however, being shown in elevation;

Fig. 3 is a perspective view of one of the 80 sleeves for preventing lateral movement of the swinging member, showing the grain extending in substantial parallelism with the axis of the sleeve; and,

Fig. 4 is a perspective view of a bearing 85 of fibrous material, such as, wood, with the grain extending transversely of the axis of the sleeve.

The spring shackle embodying the present invention is illustrated herein as applied 90 to the end of one of the side bars 1 of the frame of a vehicle, such as an automobile, and the spring of the vehicle, which comprises an upper long leaf 2, a second leaf 3 having a slot 4 in its end of greater width 95 than the stud which connects a member of the shackle to the upper leaf 2 to permit relative longitudinal movement between the leaves 2 and 3 of the spring, and a plurality of other spring leaves 5 and 6 of successively decreasing length such as are usual in 100 springs of automobiles and other vehicles.

The spring shackle illustrated in the accompanying drawings comprises a casing 7 having a dome-shaped upper end 8 and substantially parallel sides 9 and 10 provided with laterally extending arms 11 which are connected to the frame 1 by suitable rivets 105

12. The arm 11 desirably also is provided with a boss 13 to receive a bolt or rivet 14 extending through the flanges of the frame 1 to increase the rigidity of the connection 5 of the shackle casing to the frame.

The casing preferably is provided near its upper end with an internally extending boss 15 having a flat or finished surface to form an abutment for one end of one of 10 the members which support the trunnions of the swinging member and the opposite side of the casing is provided with an outwardly extending boss 16 to produce a thickened wall to receive the screw threaded head 17 15 of a bolt 18 which forms the pivot for supporting the swinging member of the shackle.

The head 17 of the bolt 18 presents a flat surface of considerable area disposed in parallelism with the surface 15 and is adapted 20 to engage the end of the other member which supports the trunnion of the swinging member. The head 17 of the bolt 18 desirably is provided with a hexagonal tool socket and is slotted radially. A screw threaded expanding plug 19 is driven into suitable complementary screw threaded sockets in opposite walls of the slot so that the head may be expanded in the aperture of the boss 16 and locked firmly therein. By this means 25 a permanent adjustment of the head 17 may be provided for the purpose of taking up wear in the bearings for the swinging member.

The movable members of the shackle comprise a swinging member which is pivotally mounted in the casing to swing about a horizontal axis only. The lower end of the swinging member is connected to the spring 30 preferably by means of a universal joint as disclosed in my prior application aforesaid.

In the preferred construction illustrated herein the swinging member comprises a body portion 20 preferably of substantially 45 cylindrical form presenting parallel flat faces and having trunnions 21 and 22 extending laterally from its opposite flat faces. The body portion of the swinging member and the trunnions are provided with a relatively large central aperture 23 which is considerably greater in diameter than the diameter of the bolt 18 upon which the swinging member is mounted. The trunnions 21 and 22 of the swinging member 50 are mounted in anti-friction bearings which are carried by the bolt 18. These bearings preferably comprise oppositely disposed cylindrical cup-shaped members having flat bases 24, peripheral cylindrical walls 25 and central cylindrical walls 26 which fit upon 55 the bolt 18.

The outer walls 25 preferably are provided with outwardly curved marginal flanges 27 which serve to strengthen the wall 60 and also provide curved inner edges 28 to

enable the sleeves and bearings for the trunnions to be more readily introduced, these sleeves and bearings preferably being composed of fibrous material, such as, oil-soaked wood, which are forced into the cup-shaped member by hydraulic pressure or otherwise. 70

In the preferred embodiment of the invention the trunnions are mounted in cylindrical bearings 29 of fibrous material, preferably oil-soaked wood, in which the grain extends transversely of the axis of the bearing, the bearings being so placed upon the trunnions that the ends of the fibres of the wood will engage the upper and lower portions of the bearing where the greatest wear occurs. 75

The bearings 29 are enclosed in cylindrical sleeves 30 of greater effective length than the length of the trunnions and bearings 29, the sleeves 30 being of a thickness to fit between the periphery of the bearings and the peripheral cylindrical wall 25 of the cup-shaped members. The inner ends of the sleeves 30 abut against the flat faces of the body 20 of the swinging member and their outer ends engage the bases 24 of said cup-shaped members. The sleeves 30 desirably are of fibrous anti-friction material, preferably of oil-soaked wood, in which the grain extends lengthwise, that is to say, substantially parallel to the direction of the axis of the sleeves so that the ends of the fibres engage the flat faces of the body and bases of the cup-shaped members. 90

In the construction of the device the anti-friction bearing members 29 of fibrous material and the sleeves 30 of fibrous material, such as, oil-soaked wood, are telescopically arranged and then forced into the cup-shaped members, the rounded edges 28 of the peripheral walls of the cup-shaped members enabling the assembled sleeve and bearing to be inserted into the cup-shaped members without scoring or otherwise injuring the sleeves. The cup-shaped members with the sleeves and bearings in them are then assembled upon the trunnions of the swinging member and this assembled construction introduced into the casing. The bolt 18 is then passed through the casing and the apertures formed by the cylindrical inner walls 26 of the cup-shaped members, the head 17 of the bolt 18 screwed into the casing until its head engages one of the cup-shaped members and forces the same laterally to cause the complementary cup-shaped member to engage firmly the flat surfaces of the casing. A nut and spring washer 31 is then placed upon the end of the bolt which projects through the casing and set up tightly. The head 17 of the bolt is then expanded by the introduction of the wedge screw 19 so that the bolt is firmly locked in the casing against displacement. 110

Means desirably are provided for preventing rotation of the cup-shaped bearing members within the casing. As illustrated herein straps 32, provided with enlarged 5 circular portions having central apertures to embrace the bolt 18, are secured to the bases of the cup-shaped members by spot welding, or otherwise, and the opposite ends of the straps are connected to the casing by 10 suitable anchoring members. The lower end of the swinging member is provided with an enlarged hollow head 33 preferably provided with an anti-friction lining 34 having a spherical socket to receive a ball 35 to 15 form a universal connection with the swinging member. The ball 35 desirably is provided with a shank 36 having a base 37 which rests upon the upper leaf spring 2. A shank 38, extending downwardly from 20 said base, passes through a suitable aperture in the spring and is connected to said spring by a sleeve 39 and nuts 40 as described in my prior application.

In the operation of the device the inner 25 ends of the sleeves 30 are firmly held between the cup-shaped members and the flat faces of the body 20 of the shackle. The diameter of these sleeves is sufficiently greater than the trunnions so that their inner ends engage 30 the body 20 of the shackle at a relatively great distance from the horizontal axis about which the swinging member oscillates. These sleeves, therefore, are so located as to exert a powerful resistance against lateral 35 movement of the swinging member. By providing sleeves of fibrous material, such as, oil-soaked wood, in which the ends are presented to the flat faces of the swinging member, an anti-friction bearing is provided 40 and also a bearing face which is not readily worn away. The inner cylindrical bearing members 29, preferably of fibrous material, such as, oil-soaked wood, also present the ends of the fibers to the trunnions and 45 produce an anti-friction bearing upon which wear is practically negligible, so that the bearings which support the trunnions of the swinging member and permit its oscillation are of a durable character and the sleeves 50 which permit the lateral movement of the trunnions are likewise of a durable character and positioned at such distance from the axis, about which the swinging member oscillates, as to effectively prevent lateral 55 movement of said member. The universal connection between the lower end of the swinging member and the spring permits torsional movements of the spring without imposing severe lateral strains upon the 60 swinging member.

By reason of the adjustability of the bolt 18 any wear upon the ends of the sleeves may be taken up readily and replacement of the bearings and sleeves can be easily made 65 by removing the bolt 18 when the parts

become worn. Where oil-soaked wood of the character described is employed for the bearings and sleeves for the trunnions there is seldom need of replacement for it is well known that bearings of oil-soaked wood, in 70 which the friction is resisted by the ends of the fibres, are of a most durable quality and in fact seldom need replenishment of oil so that the bearings constructed in the manner aforesaid, when once assembled, in the 75 shackle, will remain throughout substantially the ordinary life of an automobile without need of replacement, such wear as may be occasioned being readily taken up in the manner aforesaid. 80

It will be understood that the embodiment of the invention disclosed herein is of an illustrative character and is not restrictive and that various changes in form, construction and arrangement of parts may be made 85 within the spirit and scope of the following claims.

Having thus described my invention, what I claim as new, and desire to secure by Letters Patent, is:

1. A spring shackle for vehicles comprising a casing adapted to be secured to the frame of a vehicle, a member presenting flat faces having trunnions extending therefrom, pivotally mounted in said casing to swing about a horizontal axis, bearings for said trunnions, sleeves surrounding said trunnions of larger diameter and greater effective length than said trunnions and free from contact with the ends of said 100 trunnions abutting at their inner ends against the flat faces of said swinging member, means for preventing longitudinal movement of said sleeves and means for pivotally connecting said swinging member 105 to the spring.

2. A spring shackle for vehicles comprising a casing adapted to be secured to the frame of a vehicle, a member presenting flat faces having trunnions extending therefrom, pivotally mounted in said casing to swing about a horizontal axis, tubular sleeves surrounding said trunnions of larger diameter and of greater effective 110 length than said trunnions and free from contact with the ends of said trunnions abutting at their inner ends against the flat faces of said swinging member and engaging at their outer ends sockets rigid with said casing and means for adjusting 115 one of said sockets and means for pivotally connecting said swinging member to the spring.

3. A spring shackle for vehicles comprising a casing adapted to be secured to the 120 frame of a vehicle, a member presenting flat faces having trunnions extending therefrom, pivotally mounted in said casing to swing about a horizontal axis, tubular sleeves of 125 fibrous material of greater effective length 130

than said trunnions and free from contact with the ends of said trunnions, having their fibres extending substantially in the direction of the axis of said sleeve surrounding said trunnions, abutting at their inner ends against the flat faces of said swinging member, means for preventing longitudinal movement of said sleeves and means for pivotally connecting said swinging member to the spring.

4. A spring shackle for vehicles comprising a casing adapted to be secured to the frame of a vehicle, a member presenting flat faces having trunnions extending therefrom, pivotally mounted in said casing to swing about a horizontal axis, tubular sleeves of oil-soaked wood of greater effective length than said trunnions and free from contact with the ends of said trunnions having the grain extending in a direction substantially parallel to the axis of said sleeve surrounding said trunnions, abutting at their inner ends against the flat faces of the swinging member, means for preventing longitudinal movement of said sleeves and means for pivotally connecting said swinging member to the spring.

5. A spring shackle for vehicles comprising a casing adapted to be secured to the frame of a vehicle, a member presenting flat faces having trunnions extending therefrom, pivotally mounted in said casing to swing about a horizontal axis, outer tubular sleeves of greater length than said trunnions surrounding said trunnions and inner tubular bearings of anti-friction material intermediate of said trunnions and said sleeves, means for preventing longitudinal movement of said sleeves and means for pivotally connecting said swinging member to the spring.

6. A spring shackle for vehicles comprising a casing adapted to be secured to the frame of a vehicle, a member presenting flat faces having trunnions extending therefrom, pivotally mounted in said casing to swing about a horizontal axis, outer tubular sleeves of oil-soaked wood of greater length than said trunnions having the grain extending in a direction substantially parallel to the axis of said sleeve surrounding said trunnions, abutting at their inner ends against the flat faces of said swinging member and engaging at their outer ends sockets rigid with said casing and inner tubular bearings

of oil-soaked wood having the ends of the grain engaging the top and bottom portions of said trunnions and means for pivotally connecting said swinging member to the spring.

7. A spring shackle for vehicles comprising a casing adapted to be connected to the frame of a vehicle, a horizontal bolt mounted in said casing, cup-shaped socket members mounted on said bolt, outer tubular sleeves of oil-soaked wood having the grain extending in substantial parallelism with the axis of said sleeves, inner bearings of oil-soaked wood having the grain extending substantially vertical, a swinging member presenting flat faces engaging the inner ends of said sleeve and having alined trunnions journaled in said bearing shorter than the length of said sleeve.

8. A spring shackle for vehicles comprising a casing adapted to be connected to the frame of a vehicle, a horizontal bolt mounted in said casing, cup-shaped socket members mounted on said bolt, outer tubular sleeves of oil-soaked wood having the grain extending in substantial parallelism with the axis of said sleeves, inner bearings of oil-soaked wood having the grain extending substantially vertical, a swinging member presenting flat faces engaging the inner ends of said sleeve and having alined trunnions journaled in said bearing shorter than the length of said sleeve and an aperture extending longitudinally through said trunnions of greater diameter than that of the bolt.

9. A spring shackle for vehicles comprising a casing adapted to be secured to the frame of a vehicle, a member presenting flat faces having trunnions extending therefrom, pivotally mounted in said casing to swing about a horizontal axis, bearings for said trunnions including sleeves of larger diameter than said trunnions and free from contact with the ends of said trunnions abutting at their inner ends against the flat faces of the pivotally mounted member and means for preventing longitudinal movement of said sleeves whereby lateral movement of said swinging member will be prevented and means for connecting said swinging member to the spring.

In testimony whereof, I have signed my name to this specification.

RALPH M. LOVEJOY.
